UNITED STATES PATENT OFFICE.

JOHN IRVING WILLIAMS, OF YOUNGSTOWN, ASSIGNOR TO THE AULTMAN & TAYLOR MACHINERY COMPANY, OF MANSFIELD, OHIO.

VERTICAL WATER-TUBE BOILER.

SPECIFICATION forming part of Letters Patent No. 550,117, dated November 19, 1895.

Application filed September 5, 1895. Serial No. 561,567. (No model.)

To all whom it may concern:

Be it known that I, JOHN IRVING WILLIAMS, of Youngstown, in the county of Mahoning and State of Ohio, have invented certain new and useful Improvements in Vertical Water-Tube Boilers; and I do hereby declare the following to be a full, clear, and exact description of the invention, such as will enable others skilled in the art to which it appertains to make and use the same.

My invention relates to an improvement in vertical water-tube boilers designed more particularly to utilize the waste heat from furnaces, the objects of the invention being to uniformly heat the tubes and provide an extended heating-surface for the steam-drum, whereby the steam is superheated by the waste heat before leaving the furnace.

A further object is to provide improved means for supporting the drums and tubes within the shell.

A further object is to provide means for regulating the draft through the boiler.

With these objects in view my invention consists in the parts and combinations of parts, as will be more fully described, and pointed out in the claims.

In the accompanying drawings, Figure 1 is a view in vertical section of a boiler embodying my invention, and Fig. 2 is a transverse sectional view on the line *x x* of Fig. 1.

A represents the outer wall or shell, cylindrical in form and supported at its base on the base-ring *B*, secured on the upper ends of the uprights or posts *C*.

Leading from the furnaces *D* is the flue *E*, which latter is inclined downwardly to a point under the center of the boiler and then extends upwardly through the mud-drum *F* and terminates at a point above the mud-drum and between the water-tubes *G*. The flue *E* is supported on a masonry foundation or base *E'*, and the vertical section *E'* of the flue, projecting under the lower edge of the mud-drum, assists in supporting the drums and tubes within the shell.

The mud-drum *F* is in the form of a hollow ring with convex upper and lower faces, and is provided at intervals near its lower end on its outer surface with the flanges *F'*, which latter rest on the base-ring *B* and assist the

flue *E'* in supporting the mud-drum and superimposed parts. The mud-drum is also provided with a manhole *F''*, which latter extends through the shell, thus affording easy access to the interior of the drum for the purpose of repair or for cleaning same.

Secured to and communicating with the mud-drum are the water-tubes *G*, preferably of the same size and connected to the drum in concentric rows. In the present instance I have shown three rows of pipes, the two outer rows being vertical, while the alternate tubes of the inner row are inclined inwardly. The outer row of tubes is removed from the shell, so that the pipes of the entire series are exposed on all sides to the action of the heat.

Secured to and in direct communication with the tubes *G* is the steam-drum *I*. This drum *I* is, like the mud-drum, in the form of a hollow ring with convex upper and lower faces, the central opening or passage-way therein being, however, considerably less in diameter than the passage-way or flue through the mud-drum.

The steam-drum *I* rests with its upper surface below the upper end of the shell, and being slightly less in diameter than the interior of the shell or wall of the boiler a passage-way is thus formed around the steam-drum, which with the central flue provides a large heating-surface. The drum *I* is also provided with a manhole *I''* and with steam-pipes *I''* *I'''*, which latter pass through suitably-formed openings in the shell or wall of the boiler.

Pivoted to a suitable bearing on the stack *J* is the lever *L*. This lever carries at its inner end the depending rod *L'*, to the lower end of which is a conical damper or plug *M*, preferably made of fire-brick. This damper or plug rests directly over the central vertical flue or passage-way in the steam-drum, and hence operates to wholly or partially close the central vertical flue or passage-way, and thus cause more or less of the heat and products of combustion to be deflected around and to the outside of the drum. This lever *L* is operated by a rope or chain attached to its free end.

By this construction and arrangement of parts the several drums and tubes are sup-

ported from the bottom, and as the parts above the mud-drum are not connected to or in contact with the wall or shell the several parts are free to expand and contract without straining any of the parts.

If desired, I may place deflectors at one or more points between the drums for directing the heat and flame into contact with the tubes, and as other changes in the construction and arrangement of the several parts might be resorted to I would have it understood that I do not confine myself to the details shown, but consider myself at liberty to make such changes and alterations as fairly fall within the spirit and scope of my invention.

Having fully described my invention, what I claim as new, and desire to secure by Letters Patent, is—

1. In a vertical water tube boiler, the combination with an external shell, of a mud drum arranged in the lower portion thereof and provided with a central vertical flue or passage way, a steam drum located within the upper portion of said shell and provided with a vertical flue or passage way therethrough and having a passage way around it, a damper or plug adapted to close said passage way, and means for raising and lowering the damper or plug.

2. In a vertical water tube boiler, the combination with an external shell, of a mud drum in the lower portion thereof, a steam drum within the upper portion of said shell out of contact with said shell whereby a passage way is formed between the steam drum and external shell and provided with a vertical

flue or passage way, water tubes connecting the drums, a damper or plug for closing the vertical flue or passage way and means for raising and lowering said plug.

3. In a vertical water tube boiler, the combination with the outer wall or shell, a base ring upon which the wall or shell is supported, a central flue, and a base or foundation upon which the latter is supported, of a mud drum located in the space between the inner wall of the furnace and the outer wall of the flue, said parts so constructed that the drum rests upon and is supported by both the wall and the flue, substantially as set forth.

4. The combination with an outer shell, of a mud and steam drum, and a concentric series of pipes connecting the latter, the outer series vertical, and the inner series inclining inward toward the upper drum, substantially as set forth.

5. The combination with a shell, a central flue therein, a base or foundation upon which the latter is supported and an annular mud drum secured between the inner wall of the shell and the outer wall of the flue, of an annular steam drum having an annular space between it and the inner wall of the shell, and pipes leading from one drum to the other, substantially as set forth.

In testimony whereof I have signed this specification in the presence of two subscribing witnesses.

JOHN IRVING WILLIAMS.
